UNITED STATES PATENT OFFICE

2,458,267

ROTATING CYLINDER TYPE OF BEAN
CLEANING MACHINES

James Wallace Henry, Gooding, Idaho

Application September 21, 1945, Serial No. 617,833

2 Claims. (Cl. 209—113)

1

The present invention relates to mechanical sorters or separators and is more particularly concerned with a powered machine for separating beans and the like from foreign substances such as green night-shade berries, rock, clods and trash in the process of re-cleaning.

One of the objects of the invention is to provide a powered machine of the character described which will readily separate beans from foreign matter and deliver each to separate receptacles.

Another object of the invention is to provide a device of the character mentioned, of simpler and more compact construction than is disclosed in prior devices.

With the foregoing and other objects and advantages in view, the invention consists of the novel construction and arrangement of parts hereinafter described and claimed.

In the accompanying drawings illustrating the invention,

Figure 1 is a side elevation of the invention.

Figure 2 is a vertical longitudinal section thereof.

Figure 3 is a vertical transverse section on line 3—3 of Figure 2.

Figure 4 is a fragmentary top plan of the high speed cylinder and related parts.

Figure 5 is a fragmentary horizontal section on line 5—5 of Figure 3.

Like numerals in the description and drawings designate the same parts of construction.

The frame of the machine, which may be constructed of light steel or wood, is rectangular and comprises longitudinal side bars 1, vertical bars 2 mounted on a portable base 3 and vertical supports 4 for the open top and bottom hopper 5. The supports 4 are secured to side bars 1 intermediate their ends. Hopper 5 is provided at its lower front with a transverse discharge port or opening 5a which can be regulated by a vertically adjustable gate 6. The adjustment is made by means of a threaded bolt 7 at each side working in horizontally disposed arms 8 secured to the top of the gate. Bolts 7 are reduced at the ends and rotatably contained in lugs 9 which are secured to the front of the hopper. Hand wheels 10 are provided for turning of the bolts.

The floor 11 of the hopper is separated therefrom and supported on transverse rolls 12. The substantially horizontal floor is stationary but tiltable and its front which extends forwardly from the hopper 5 to constitute a ledge, is beveled on the underside, as at 11a. Metal strips 14 are secured to the underside of the floor 11 adja-

2

cent the vertical supports 4 and are shaped with stirrup-like bends 15 at front and rear. These are for the rolls 12 to pass through. Extending eccentrically from the ends of the rolls are stud spindles 16 which are mounted in bearings 13 attached to the supports 4. These spindles are rotatable by crank handles 17 and the rotation thereof imparts a cam-like movement to the rolls which is adapted to tilt the floor 11 as may be desired.

By adjusting floor 11 through rollers 12 the distance of the forward edge above cylinder 24 can be definitely fixed for any particular size of beans or the like. This adjustment is important as the distance between the forward edge of floor 11 and cylinder 24 should be sufficient to permit the beans to roll downward between the floor and cylinder but not so great as to permit the beans to bounce on the cylinder.

A plate 18 is interposed between the open bottom of the hopper and floor 11 and rests on the latter. It extends, at the front, through the opening 5a and to a point back of the front edge of the floor. At its rear the plate extends rearwardly a suitable distance back of the hopper where it is attached by shackle-bolts 19 to the arms 20. The opposite ends of arms 20 are pivotally attached to levers 21 which are pivoted to frame members 2 at 21a and have their other ends pivoted to links 22 connected to eccentric studs 25 on the ends of the cylinder shaft 23 of a high speed rotary cylinder 24. The eccentric action of the studs rocks the levers 21 and reciprocates plate 18 producing a slow movement of the beans toward the cylinder 24.

Cylinder 24 is constructed of metal with a smooth, highly polished surface and its shaft is rotatably mounted in bearings on the forward end of the frame. This cylinder is connected by pulley 26 and belt 27 to a motor M and is adapted to revolve at a high rate of speed so as to carry off foreign matter once it obtains traction thereon. The cylinder is positioned in advance of the hopper floor 11 but its perimeter is separated from the front edge thereof by a suitable gap, as indicated. It may desirably be positioned vertically so that its top point is above the plane of floor 11. In front and back of the cylinder are receiving bins 28 and 29 which are attached to the frame of the machine and provided at the bottom with discharge spouts 30 and 31 for the purpose to be explained hereinafter.

In operation the beans, which are usually smooth and commingled with foreign matter, which is usually rough, are fed into the hopper

and thence through opening or port 5a onto the cylinder and the gate adjusted to permit the proper amount to pass through to the fast revolving cylinder 24. It is fed forward to the gap by the reciprocating plate 18 which is actuated by the eccentrics on shaft 23. As the matter is pushed over the ledge of stationary floor 11 it falls vertically on the polished surface of the rapidly revolving cylinder which, it will be noted, is rotating away from the floor 11. Because of the high speed of the cylinder the only matter contacting it which will obtain enough traction to remain thereon will be the foreign substances. The beans being smooth and unable to obtain traction will fall off the cylinder and down the gap between the floor and cylinder. They are thus separated from the foreign matter and drop into rear bin 29 while the foreign matter is carried over and drops from the cylinder into bin 28. If the mixture is being fed to the cylinder too fast or too slow the flow can be adjusted by tilting plate 18, as desired.

While the described embodiment of the invention is deemed preferable on account of its extreme simplicity and effectiveness, I am aware that the invention can be embodied in various other specific forms without departing from the spirit thereof, and I therefore desire the present embodiment to be considered as illustrative and not restrictive and refer to the appended claims, rather than to the foregoing description to indicate the scope of the invention.

Having thus described my invention, what I claim as new and desire to secure by Letters Patent is:

1. In combination, an open bottom hopper provided with a frontal discharge opening adjacent its bottom, a tiltable substantially horizontal floor provided with a frontal ledge, a reciprocatory, superimposed plate adapted to move the contents of the hopper forwardly over said ledge, a rotary

cylinder provided with a highly polished surface and positioned longitudinally adjacent the ledge of said floor but separated therefrom by a transverse gap and positioned vertically so that the upper surface of its periphery is above said ledge, a motor adapted to rotate the cylinder at a high rate of speed in a direction away from the hopper, a vertically adjustable gate adapted to regulate the flow of matter through the discharge opening of the hopper and means for reciprocating said superimposed plate to feed material from the hopper on to the cylinder.

2. The device set forth in claim 1, the said reciprocating means comprising rocker arms operated by eccentric studs on the ends of the cylinder shaft and adapted to operate pivotal arms connected to the rear end of said plate and impart a reciprocatory movement thereto.
